GRINDING MACHINE WITH CRUSH WHEEL
DRESSING MECHANISM

Paul A. Grobey, Springfield, Vt., assignor to
Bryant Chucking Grinder Company, Springfield, Vt., a corporation of Vermont

Application October 5, 1951, Serial No. 249,880

10 Claims. (Cl. 51--5)

1. This invention relates to grinding machines, and while not restricted thereto, is particularly applicable to machines wherein the grinding wheel has a contour of a shape difficult to dress by means of a single dressing point or diamond, so that crush dressing is particularly advantageous.

One of the objects of the invention is to provide dressing mechanism, more particularly of the crushing type, with means for automatically presenting it to the wheel and removing it therefrom after a predetermined number of grinding operations have been completed.

Still another object of the invention is to provide for feed of a pair of crushing rolls from diametrically opposite sides against the wheel, thereby to relieve the grinding wheel mounting from unbalanced pressure due to the dressing operation.

Still another object is to provide for relative feed between the work holder and the grinding wheel to compensate for wheel size reduction due to wear and dressing.

Still another object is to provide a wheel drive for dressing slower than normal grinding speed.

For a more complete understanding of this invention reference may be had to the accompanying drawings in which:

Figure 1 is a fragmentary top plan view of an internal grinding machine embodying the invention, the dressing mechanism being shown in dressing position.

Figure 2 is a fragmentary front elevation of the same, the dressing mechanism being shown retracted.

Figure 3 is a sectional view on line 3--3 of Figure 1.

Figure 4 is a fragmentary rear elevation of the machine, parts being broken away.

Figures 5 and 6 are detail sectional views on lines 5--5 and 6--6, respectively, of Figure 3.

Figures 7, 8 and 9 are detail sectional views on the correspondingly numbered section lines of Figure 1.

Figure 10 is a detail sectional view to a larger scale on line 10--10 of Figure 2.

Figure 11 is a view similar to Figure 7 but showing the parts in different relative positions, and with certain additional parts.

Figure 12 is a detail sectional view on line 12--12 of Figure 2.

Figure 13 is a detail sectional view on line 13--13 of Figure 12.

Figure 14 is a fragmentary side elevation

2 showing the main cam shaft and feed shaft and related parts.

Figure 15 is a side elevation, partly broken away and in section, of the wheel head and its slow speed crush dress driving mechanism clutched thereto.

Figures 16 and 17 are detail sectional views to a larger scale on lines 16--16 and 17--17, respectively, of Figure 15.

Figure 18 is an elemental wiring diagram for the machine.

Referring first to Figures 1 and 2, the grinding machine as shown comprises a base 1 which supports wheel head 2 provided with a grinding wheel shaft 3 carrying the grinding wheel 4. This shaft 3 may be integral with the armature shaft of a high speed motor, the casing for which is shown at 2a (Figure 15). Also mounted on the bed 1 is a work head 5 having journaled therein a suitable work spindle provided with a work holder 6 at one end, and a belt pulley 7 at the other, over which passes a drive belt 8 leading to any suitable driving motor 5M (Figure 18), by which the work spindle may be rotated so as to present rotating work to the grinding wheel 4. The work head is movable on the bed 1 transverse to the direction of the wheel spindle 3, and it is so moved to produce relative feed between the grinding wheel 4 and work carried by the work spindle as is well known in the art.

The work head 5 is provided with depending bearings one of which is shown at 10 in Figure 12 and which are mounted on ways provided with dust-excluding bellows 11 and 12, as shown in this figure, which surround the ways and seal them to the depending portions 10 of the work head. The work head is provided with a wall member 15 carrying an abutment 16 which is pressed against the end of a feed shaft 17, as by a weight 18 connected through a cable 19 to the head 5 and passing over a pulley 20.

As shown in Figure 13, the shaft 17 is threaded as at 25 within an internally threaded nut 26 to which is keyed a feed lever 27. By rocking this feed lever it is evident that the shaft 17 may be moved axially without being rotated. This provides for the normal feed of the work head with respect to the grinding wheel, but a further feed is provided to compensate for wheel wear and truing which reduce the size of the wheel. This is produced by rotating the feed shaft 17. For this purpose it has keyed thereto at one end a gear 28 which is connected through a gear 29 to a shaft 30 (see Figure 2), and this shaft 30 may be stepped around in feed direction by a ratchet

feed mechanism at 31 having a dog 32 which engages a ratchet wheel 33 (see Figure 10) secured to the shaft 30. This ratchet mechanism is actuated by the rocking of a bell crank lever 34 fulcrumed on the shaft 30, one arm of which is connected through a link 35 to a T-shaped lever 36 fulcrumed at 37 to a fixed portion of the machine. A second arm 38 of this lever is connected through an adjustable link 39 to a flexible pull cable 40 which may be actuated by means which will later be described.

In normal grinding operations, the grinding wheel 3 is driven at high speed through the high speed driving motor of which the shaft 3 forms a portion of the armature. However, at certain times it may be desired to dress the grinding wheel, and particularly where this grinding wheel is of somewhat intricate shape which it is difficult to produce by the motion of a single truing point, it may be desired to effect the truing by a crushing operation. In order to effectively crush dress such a wheel it is necessary to reduce its rotating speed very greatly. For this purpose there is provided a slow speed driving motor 1M, which, as shown, is mounted on the casing 2a of the wheel head which houses the high speed grinding wheel motor.

The driving connections from the slow speed motor 1M to the wheel shaft 3 are illustrated best in Figures 15 to 17. As shown in Figure 15, the drive shaft 50 of the low speed motor 1M is provided with a pulley 51 about which passes a belt 52 which also engages about a pulley 53 secured to a hollow shaft 54. This hollow shaft 54 is journaled in spaced bearings 55 and 56 in a bearing box 57 shown as formed integral with a stationary end wall 58 for the wheel housing 2a. Within this housing the shaft 54 is provided with a spider 60 within the outer portion of which are pivoted, as on pins 61, a plurality of friction clutch shoes 62, four such shoes being shown in Figures 16 and 17, arranged symmetrically about the axis of the hollow shaft 54. The inner ends of these shoes 62 are pressed inwardly radially as by springs 63 seated in a socket 64 in the shoes and engaging the inner face of a ring 65 which surrounds the shoes 62. The inner ends of the shoes 62 are provided with friction pads 66 which may engage the periphery of clutch pulley 67 which is secured to the rear end of the wheel shaft 3. This arrangement provides a frictional drive for the shaft 3 from the hollow shaft 54 which is driven by the motor 1M at the slow speed, this slow speed drive being accomplished when the high speed motor portion of the wheel drive is deenergized and the shoes 62 are in driving engagement through the friction means with the shaft 3.

Means are provided for withdrawing the shoes 62 from such frictional engagement to permit the wheel drive to be produced by the high speed drive. This is accomplished by pressing to the left, as shown in Figure 15, a rod 70 which passes axially through the hollow shaft 54 and at its inner end is provided with a tapered portion 71 which engages a series of balls 72 and presses each of these balls outwardly, forcing outwardly radially arranged pins 73, the outer ends of which may engage the shoes 62 somewhat inwardly of their pivots 61 and force them outwardly against the pressure of the springs 63. This operatively disconnects the slow speed drive for the grinding wheel. This axial position of the bar 70 is controlled by the angular position of a T-shaped lever 75 fulcrumed at 76 on a

bracket 77 secured to the stationary wall member 58. One arm 79 of this lever 75 is provided with an adjustable stop 80 which may engage a boss 81 on the bracket 77 to limit the pivotal motion of the lever 75 in one direction. A second arm 82 of this lever 75 bears against the outer end of the bar 70, and a finger 83 attached thereto as by a screw 84, is provided with a portion which engages the left hand side of a head 86 on the bar 70. Thus as the lever 75 is rocked, the bar 70 is moved positively in either direction. A third arm 87 of the lever 75 has connected thereto one end of a cable 88 which passes axially through a cable cover 89 held in a clamp 90 carried by a bracket 91 secured to the bracket 77. Axial motion of the cable 88, it will be clear, will serve to rock the lever 75 and thus control the axial position of the bar 70. By this means the operative connection and disconnection of the slow speed drive motor M to the wheel spindle 3 is effected.

The wheel dressing mechanism is carried by and is thus movable with the work head, but it is pivotally secured thereto as on the pivot shaft 100. It comprises a supporting frame member 101 to which the pivot 100 is secured and which carries slidably a pair of parallel spaced bars 102. The outer ends of these bars 102 have secured thereto a head 103. As shown in Figure 5, this head 103 has secured therethrough a bearing member 104 which has journaled therein a shaft 105. This shaft 105 is provided with a shoulder 106 which is drawn against the inner raceway of one of the ball bearings 107 of the bearing member as by a nut 108 threaded on its reduced diameter end portion and bearing against the inner raceway of a second similar ball bearing 109. A cover plate 110 bridges over the nut 108 and one end of the bearing member 104, and screws 111 secure the cover plate and the bearing member 104 in position. The opposite end of the shaft 105 is provided with a head 115 over which may be engaged a crush dressing wheel 116 having its periphery shaped complementary to the desired configuration of the grinding wheel 4. This crush dressing wheel may be removably secured to the head 115 as by a headed plug 120 and is free to be rotated by the rotation of the grinding wheel when it is brought into contact therewith. By a similar mounting a crush dressing wheel 121 is supported on a slide 122 having a shank 123 longitudinally slidable on the frame member 101. This shank 123, as shown best in Figure 6, is of trapezoidal cross section and may be clamped rigidly in its slideway by the removable guide member 127 which is secured in position by screws 124.

The bars 102 are slidable through the slide 122 and their ends opposite to the head 103 are secured in a frame member 125. This frame member carries an adjustable stop screw 126 which limits the approach between the frame 125 and the head 122, these parts being pressed together as far as permitted by the stop 126 by coil springs 128 having their ends secured in eyebolts 129 in these parts. These springs therefore tend to separate the two crush dressing wheels 116 and 121 as far as is permitted by the stop 126 at such a distance that they may straddle the grinding wheel 4 at substantially diametrically opposite sides when this mechanism is in the full line position shown in Figure 3. As the frame 101 is pivotally supported, it may be rocked to the dotted line position shown 75 in Figure 3 with the crush dressing wheels 116

and 121 out of contact with the grinding wheel 4, and this is the normal position of the parts during the grinding operation. However, when crush dressing is to be effected, the crush dressing mechanism is brought to its full line position shown in Figure 3, and the crush dressing wheels are pressed heavily against opposite sides of the grinding wheel to effect the dressing operation, these dressing wheels being free to revolve with the grinding wheel.

The rocking of the crush dressing wheels into dressing position causes a cam member 130 carried by the frame 125 by pivots 131 and 132, the latter being mounted in a slot 133 in the frame and adjustable therein by the adjustment screw 134, to ride into contact with a follower roll 135 carried by a lever 136 pivoted at 137 on a bracket 138 secured to a bracket member 140 fixed to the machine bed 1. The lower end of the lever 136 is connected through a link 145, adjustable in length, to a bracket 146 depending from the work head 5. Riding of the cam member 130 along the follower 135 moves the frame 125 to the right, as viewed in Figure 3, pulling the crush dressing wheel 116 toward the axis of the grinding wheel 4. Motion of the work head to the left, as viewed in Figure 3, thus acts to press the follower roll 135 against the cam 130 and pull the rods 102 in a direction to move the crush dressing roll wheel 116 toward the axis of the wheel 4, and the motion of the work head in this direction carrying with it the pivot 103 to which the slide 122 is secured by the grip fit of its shank 123 in the guideway 101 as previously described, moves the crushing wheel 121 in the opposite direction and against the grinding wheel, thus squeezing the grinding wheel 4 between them with an equalized pressure. This lever and link mechanism effects the compensating feed for wheel wear and truing, the two arms of the lever 136 being of equal effective lengths.

The various operations of the machine are actuated by a series of electric motors. The motor 1M which drives the grinding wheel shaft 3 at the low speed, and the high frequency, high speed drive for this shaft have previously been described. The various usual steps of the grinding cycle, such as relative approach and retraction between the grinding wheel and the work, are actuated by a motor 4M shown in the diagram of Figure 18 and which drives a main cam shaft 150 shown in Figure 14 having cams for accomplishing these functions, and as these are old and well known no specific showing of them is contained herein. This cam shaft is also provided with a cam 151 which acts at one angular position of the cam shaft to momentarily actuate a switch LS8, after which this switch returns to its former position. It also carries a cam 152 which at certain times may close a normally open switch LS6. This switch LS6, as will later appear, is in the control circuit for a feed motor 6M shown both in the diagram of Figure 18 and in Figure 14. This motor 6M is connected by the belt 153 to a shaft 154 connected through a worm gear drive with a shaft 155. This shaft 155 carries a cam 156 which cooperates with a follower 157 carried by a lever 158. This lever 158 is fulcrumed at 159 and its opposite end is connected through a link 160 to the arm 27 of the feed mechanism shown best in Figures 2 and 13 so that as the cam 156 is rotated it lifts the arm 27 and produces a feed actuation of the feed shaft 17. This shaft 155 also carries cams which at suitable times close the normally open switches LS12 and LS7. The

arrangement by which certain of the machine controls are effected by cams on a main cam shaft and the feed is effected by a second feed cam shaft, the two cam shafts being rotated alternately while the other is stationary is not claimed herein, but forms subject matter of my application Serial No. 236,297, filed July 12, 1951, for Automatic Grinding Machine.

The motion of the dressing wheel mechanism from the dressing position shown in full lines in Figure 3 to the idle position shown in dotted lines is produced by a cam 170 carried by a dressing cam shaft 171. This cam shaft 171 is rotated by a motor 3M shown in Figure 1 and diagrammatically in Figure 18. The shaft 172 of this motor is connected through a belt drive at 173 with a shaft 174 of a suitable reducing gear mechanism (not shown) within a case 175, to the shaft 171. The cam 170 acts upon a follower roll 180 (see Figure 7) which is carried by an arm 181 fixed to the shaft 100, to which is also fixed the truing mechanism as previously described. This arm 181 has a stop member 182 which cooperates with an adjustable stop screw 183 and when the parts are in this position, as shown in Figure 7, the truing mechanism is in its operative full line position shown in Figure 3. The cam 170 has a lobe 184, however, which on rotation of the shaft 171 in the direction of the arrow shown in Figure 7 and to the position shown in Figure 11, may contact and depress the follower roll 180 and swing the truing mechanism up into the inoperative dotted line position shown in Figure 3 and in Figure 11. This cam 170 also carries a cam projection 185 which lifts a follower roll 186 of a normally closed switch LS11 to hold this switch open when the dressing mechanism is in retracted position.

The cam shaft 171 also carries a second cam disk 190 (see Figure 8) with which cooperates a follower roll 191 on a lever 192 fulcrumed at 193 on a stationary bracket 194. This follower 191 is held in contact with the cam disk 190 as by a spring 195, and to its upper end is connected through a link 196 a flexible cable 48 which is slidably through a cable cover 198 held by a bracket 199. This cable 48, which as previously described, extends to the feed compensating mechanism by which the feed between the work head and the wheel head is actuated a predetermined amount whenever dressing is being effected. As shown this mechanism is given four actuations during each driving operation. This cam shaft 171 also carries a third cam 200 (see Figures 9 and 11) which has a cam lobe 201 which at the end of the crushing engages a follower 202 carried by a lever 203 fulcrumed at 204 on the bracket 199. The follower 202 is normally held toward the cam 200 as by a spring 205 and its outer end is connected through an adjustable link 206 to the flexible cable 48 which is slidably housed within the cover 198. As previously pointed out, pulling of this cable with the parts in the position of Figure 11 pushes the rod 70 releasing the low speed drive and allows the high speed drive to become effective on the grinding wheel 4. The cam shaft 171 stops in the position of the parts shown in Figure 11.

Referring to the diagram in Figure 18 showing the parts in idle position, the high frequency high speed motor 2M which drives the grinding wheel during the grinding portion of the cycle is driven from a suitable high frequency source, comprising the high frequency lines 250, 251, 252, through a main switch 253. When this

main switch 253 is closed, the motor 2M is controlled by other mechanism shown in the lower portion of this figure, energized by a low frequency low voltage control circuit derived from the secondary 255 of a transformer 253, the primary 257 of which receives its power from the normal frequency lines 260, 261, 262 through the main switch 264. The motors 1M, 3M, 4M, 5M and 6M all derive their power from the lines 260, 261 and 262. The crusher cam motor 3M and the crusher slow speed motor 1M are controlled simultaneously by the same mechanism, so that when the crusher cam allows the crushing mechanism to swing into operative position, the slow speed drive for the wheel is started, the 15 fast speed drive for this motor having been disconnected.

The operation may be understood from an inspection of Figure 18. Closing of the master start switch 270 establishes a circuit from a transformer secondary 255 through leads 271 and 269, switch 270, lead 272, closed stop switch 337, leads 338 and 339, control switch 7m and lead 340 to lead 277 back to the transformer secondary. Closing of the control switch 7m closes a holding switch 239 which is shunted around the master switch 270. The control switch 7m when closed may also start into operation various auxiliary apparatus (not shown) such as lubrication and coolant circulation apparatus, as is well known. Closing of the master start switch also starts the high speed grinding wheel motor 2M as it closes a circuit from lead 273 through lead 276 and closed C switch 336, CR3 switch 365, CR4 switch 366 and the control mechanism 2m for the motor 2M.

The operation of the machine is then started by closing the switch 285 which closes a control circuit from the lead 272 through leads 273, 286, switch 285, lead 287, control 4m, lead 288 to the lead 277. The control 4m then starts the main cam motor 4M shown in the upper portion of Figure 18. Also a holding 4m switch 289 shunted about the switch 285 is closed so that the main cam motor 4M continues in operation even after the switch 285 is allowed to open. Each rotation of the main cam shaft 150 momentarily moves a switch LS8 from its upper to its lower position shown in Figure 18, establishing a circuit from lead 298 through lead 299, switch LS8, lead 300, counting mechanism CNTR and lead 301 to the lead 277. Until the predetermined number of actuations of the counter corresponding to the desired number of grinding cycles between trunings of the grinding wheel have been had nothing results from this actuation of the switch LS8 except to deenergize the relay CR1 which, as will later appear, is energized at the time the switch LS8 is so moved.

The rotation of the main cam shaft 150 acts 60 by suitable cam mechanism driven thereby to advance the wheel into operative relation to the work, whereupon it closes the switch LS4 and immediately thereafter closes the switch LS6. Closing of the switch LS4 closes a circuit from the lead 287 through the lead 289, the switch LS4, lead 282, motor control 5m and lead 283 to the lead 277. This starts rotation of the work spindle by energizing the work rotating motor 5M. Energizing the relay CR2 opens the CR2 switch 316, opening the clutch connection between the cam motor 4M and the cam shaft 150 and closes the CR2 switch 317 and applies the brake, stopping the rotation of the main cam shaft.

5 Energizing the relay CR2 closes the CR2 switch 310 which closes a circuit from lead 298 through lead 311, closed switch 310, closed CR4 switch 312, lead 313, feed motor control 6m and lead 314 to the lead 277. This closes the feed brake switch 315 to release this brake so that the feed motor 6M turns the feed cam shaft 155.

The rotation of the feed cam shaft 155 first acts to close the switch LS7, which maintains the CR2 relay closed, by establishing a circuit around the open switch LS6 from the lead 298 through lead 326, switch LS7, and lead 325 to lead 308. Toward the end of a complete rotation of the cam shaft 155 it momentarily closes the switch LS12 and thereafter permits the switch LS7 to open. The momentary closing of the switch LS12 closes a circuit from the lead 298 through the lead 320, switch LS12, leads 321 and 322, relay CR1, and lead 323 to lead 277. Closing of the relay CR1 closes its holding CR1 switch 324, which with the switch LS8 in its upper position maintains the relay CR1 energized. Opening of the switch LS7 then with the CR1 switch 307 open through the energization of the relay CR1 deenergizes the relay CR2. Change thereafter of the switch LS8 to its lower position deenergizes the relay CR1.

30 Deenergizing this relay CR2, then actuates the switch 317 to release the brake and the switch 316 to close the clutch, re-starting the main cam shaft 150 and the rotation of this main cam shaft continues for another portion of the cycle. This action continues, alternately rotating the main cam shaft 150 and the feed cam shaft 155 until the number of complete grinding cycles for which the counter C has been set has been reached. When this has been reached, the actuation of the switch LS8 to its lower position, as shown in Figure 18, causes the counter to open the counter switch 336 in the circuit to the high frequency grinding wheel motor 2M, so that this motor stops. The C switch 335 is closed and this establishes a circuit from the lead 272 through the closed stop switch 337, leads 338 and 339, lead 339, C switch 335, lead 340, the crusher cam starting mechanism 3m and lead 341 to lead 277. It also closes the circuit through the brake 344, which is a spring-closed electrically-released brake, for the cam shaft motor 3M so that the crusher cam motor 3M starts. Energizing of the control 3m closes the 3m switch at 350 which with the closed C switch 335 establishes a holding circuit from lead 273, through lead 351, 3m switch 350, and lead 339, C switch 335 to lead 340. The closing of the C switch 335 also energizes the relay CR4. This opens the CR4 switch 366 in the control circuit for the motor control 2m and it also closes a CR4 switch 367 which by-passes the switches LS6 and LS7 and closes the relay CR2. Closing of this relay CR2, as before noted, stops the rotation of the main cam shaft, opening the CR4 switch 312 in the feed motor circuit 6m so that the motor 6M cannot operate during the dressing operation. The crusher wheel motor 1M being controlled with the crusher cam motor 3M also operates when the crusher cam motor 3M starts to rotate. The rotation of the crush cam motor 3M from its idle position of Figure 11 causes the cam lobe 184 to release the follower 180, allowing the crush dressing mechanism to drop to the full line operative position of Figure 3 and the cam lobe 201 releases the follower 202 to the position shown in Figure 9. This latter action allows 40 the cable 88 to be moved by the spring 205 in

direction to withdraw the rod 70 into the position shown in Figure 15 wherein the slow speed wheel drive from the motor 1M is effective to drive the grinding wheel at slow crushing speed.

Continued rotation of the dressing cam shaft 171 causes the cam 190 and the spring 195 to alternately push and pull on the cable 40 to step around the feed ratchet wheel 33 (see Figure 10) and feed the crush dressing wheels against the grinding wheel. This dressing action takes place until the dressing cam shaft 171 has completed one revolution and is in the position of Figure 11 where the cam lobe 184 acting on the follower 180 has returned the dressing mechanism to its inoperative dotted line position of Figure 3, the follower 202 has been lifted, pulling the cable 88 and opening the friction drive connection between the motor 1M and the grinding wheel by projecting the rod 70 between the rods 73, and the stop switch LS11 has been closed by the cam element 185 as shown in Figure 11.

Closing of the switch LS11 establishes a circuit from the lead 273 through switch LS11, lead 360, relay CR3 and lead 361 to the lead 271. The circuit is also completed from the lead 360 through the lead 362 and counter re-set device 363 to the lead 271 which sets the counter C back to starting position for a new series of grinding cycles before the truing mechanism will again be operated.

Closing of the relay CR3 closes the relay CR3 switch at 365 which starts the high frequency grinding wheel motor 2M. It also opens the CR3 switch at 361 which deenergizes the relay CR4, stops the crusher cam motor 3M and the crusher wheel motor 4M, and allows the brake 348 to stop the crusher cam motor. The parts are then in position for repetition of the grinding cycle.

From the foregoing description of an embodiment of this invention it should be evident to those skilled in the art that various changes and modifications may be made without departing from its spirit or scope.

I claim:

1. A grinding machine having a grinding wheel, means selectively operatively connectible thereto for rotating said wheel at a higher grinding speed or at a lower crushing speed, a wheel crushing mechanism comprising a pair of spaced freely rotatable crushing wheels between which said grinding wheel may be engaged, a support carrying said crushing wheels, means mounting said support for motion from and to a position wherein said crushing wheels are positioned on substantially diametrically opposite sides of said grinding wheel, means operatively connected thereto for moving said support from and to said position and for moving said crushing wheels toward and from each other to crush dress and then retract from said grinding wheel when said support is in said position, a cycle counter operatively connected to said grinding machine to be actuated by one count by each grinding cycle of the machine, and means operatively connected to and actuated by said counter at the completion of a predetermined number of grinding cycles to actuate said support-moving means to position said crushing wheels in said position and to move said crushing wheels toward each other to crush dress said grinding wheel and thereafter to retract said crushing wheels and remove said support from said position.

2. A grinding machine having a grinding wheel, means operatively connectible thereto for rotat-

ing said wheel at high grinding speed, means operatively connectible thereto for rotating said wheel at a slower crushing speed, a work holder, means for feeding said holder and wheel relatively, a wheel crushing mechanism movable between an operative and an inoperative position with respect to said grinding wheel, means operatively connected thereto for acting automatically after a predetermined number of grinding cycles to render said high speed rotating means inoperative and said slow speed rotating means operative to drive said grinding wheel, and to move said mechanism from inoperative to operative position to crush dress said wheel, said wheel crushing mechanism comprising a pair of spaced freely rotatable crush dressing wheels between which said grinding wheel may be engaged, means for moving said crushing wheels from and toward each other, and means operatively connecting said feeding means and crushing wheel moving means for actuating said feeding means in accordance with the motion of said crushing wheels toward each other to compensate for reduction in grinding wheel diameter through wear and dressing in the relative positions between said work holder and grinding wheel.

3. A grinding machine having a rotary grinding wheel, means for rotating said wheel, a wheel crushing mechanism mounted for swinging motion from and toward said grinding wheel, said mechanism comprising a pivotally mounted frame, a pair of hard crushing wheels mounted for free rotation in said frame and for relative motion from and toward each other, said crushing wheels being disposed relative to the pivotal mounting of said frame and said grinding wheel to be positioned on diametrically opposite sides of said grinding wheel when said mechanism is swung toward said grinding wheel, and cam means operatively related to said crushing wheels and actuated by the motion of said mechanism toward said grinding wheel to move said crushing wheels into contact with said grinding wheel.

4. In a grinding machine having a rotary grinding wheel and means for rotating said wheel, a crush dressing mechanism pivotally mounted on said machine for swinging between an operative and an inoperative position, and having a pair of movably mounted freely rotatable crushing wheels supported for crushing engagement with said grinding wheel and for rotation thereby when said mechanism is in said operative position, means operatively connected to said mechanism actuatable to move said mechanism from said inoperative to said operative position, and means operatively connected to said crushing wheels and effective to move said crushing wheels into pressing contact with said grinding wheel by the movement of said mechanism into operative position.

5. In a grinding machine having a rotary grinding wheel and means for rotating said wheel, a crush dressing mechanism pivotally mounted on said machine for swinging between an operative and an inoperative position, and having a pair of movably mounted freely rotatable crushing wheels supported for crushing engagement with said grinding wheel and for rotation thereby when said mechanism is in said operative position, means operatively connected to said mechanism actuatable to move said mechanism from said inoperative to said operative position, and means operatively connected to said crushing wheels and effective to move said crush-

ing wheels into pressing contact with said grinding wheel by the movement of said mechanism into operative position and releasing said pressure by motion of said mechanism away from operative position.

6. A grinding machine having a rotary grinding wheel, grinding wheel crusher mechanism comprising a frame, a pair of crushing wheels carried by said frame and movable from and toward the axis of said grinding wheel, and cam means operatively connected to said crushing wheels and including a cam having a plurality of active portions constructed and arranged to move and press said crushing wheels against said grinding wheel intermittently a plurality of times during each crushing action by continuous motion of said cam means.

7. In a grinding machine having a rotary grinding wheel and means for rotating said wheel, a crush dressing mechanism pivotally mounted on said machine for swinging between an operative and an inoperative position, and having a pair of movably mounted freely rotatable crushing wheels supported for crushing engagement with said grinding wheel and for rotation thereby when said mechanism is in said operative position, means operatively connected to said mechanism actuatable to move said mechanism from said inoperative to said operative position, a cam carried by said mechanism, a follower engaged by said cam when said mechanism approaches said operative position, and operative connections from said cam to said crushing wheels effective through the action of said cam on said follower to move said crushing wheels toward the axis of said grinding wheel as said mechanism is moved fully to said operative position.

8. In a grinding machine having a bed, a rotary grinding wheel carried by said bed and means for rotating said wheel, a crush dressing mechanism comprising a frame pivotally mounted on said bed for swinging between an inoperative and an operative position, said frame being slidable transversely of said pivot and having a pair of freely rotatable crushing wheels supported for crushing engagement with said grinding wheel and for rotation thereby when said mechanism is in said operative position, one of said crushing wheels being journaled on said frame and the other of said crushing wheels mounted for movement on said frame toward and from said one crushing wheel, means operatively connected to said mechanism actuatable to move said mechanism from said inoperative to said operative position, a cam carried by said frame, a follower carried by said bed and with which said cam engages when said mechanism approaches said operative position for moving said frame in a direction to move one of said crushing wheels toward the axis of said grinding wheel, and connections from said frame to the other of said crushing wheels causing the cammed motion of said frame to move the other of said crushing wheels toward said grinding wheel axis.

9. In a grinding machine having a bed, a carriage mounted for linear motion on said bed, a rotary grinding wheel journaled in said carriage on an axis transverse to its direction of motion

on said bed, means for rotating said wheel, a crush dressing mechanism pivotally mounted on said bed for swinging between an inoperative and an operative position and having a pair of freely rotatable crushing wheels supported for crushing engagement with said grinding wheel and for rotation thereby when said mechanism is in said operative position, means interconnecting said crushing wheels for equal and opposite movement from and toward each other with reference to the pivotal mounting of said mechanism, means operatively connected to said mechanism actuatable to move said mechanism from said inoperative to said operative position, a cam carried by said mechanism, a lever pivoted to said bed about an axis transverse to the direction of motion of said carriage, a link connecting one end of said lever to said carriage, a follower carried by the opposite end of said lever and with which said operative cam engages when said mechanism approaches said position for moving said cam, and operative connections between said cam and crushing wheels causing the motion of said cam by engagement on said follower to move said crushing wheels toward each other and into engagement with said grinding wheel.

10. In a grinding machine having a rotary grinding wheel and means for rotating said wheel, a base, a slide mounted on said base for motion toward and from said grinding wheel, crush dressing mechanism pivoted on said slide and swingable about said pivot between a position for dressing said wheel and an inoperative position, a cam carried by said mechanism, a lever fulcrumed on said base and having a follower cooperating with said cam, said dressing mechanism comprising a pair of spaced freely rotatable crushing rolls, one of said rolls being mounted for motion in the direction of said slide on said base when said mechanism is in the dressing position, said cam and follower being arranged to move said one roll toward said grinding wheel when said mechanism is being swung to wheel dressing position, and an operative connection between said lever and slide causing motion of said slide to move the other of said rolls toward said grinding wheel in the opposite direction to the motion of said one roll as said one roll is so moved on the swinging of said mechanism toward wheel crushing position.
